UNITED STATES PATENT OFFICE.

JOHN JOHNSON GULDHANG, OF STOUGHTON, WISCONSIN.

WINDOW-BLIND.

SPECIFICATION forming part of Letters Patent No. 349,252, dated September 14, 1886.

Application filed May 17, 1886. Serial No. 202,380. (No model.)

To all whom it may concern:

Be it known that I, JOHN JOHNSON GULDHANG, a resident of Stoughton, in the county of Dane and State of Wisconsin, have invented 5 certain new and useful Improvements in Window-Blinds; and I do hereby declare that the following is a full, clear, and exact description of the invention, which will enable others skilled in the art to which it appertains to 10 make and use the same, reference being had to the accompanying drawings, which form a part of this specification, and in which—

Figure 1 is a view from the inside of my improved window-blind. Fig. 2 is a vertical sectional view on line α α , Fig. 1. Fig. 3 is a perspective view of one of the slats, seen from the inner side. Fig. 4 is a similar view of a slat seen from the outer side, the slat being one of the slats at either the upper or lower 20 ends of a series, and Fig. 5 is a perspective view of the adjusting-rod.

Similar letters of reference indicate corresponding parts in all the figures.

My invention has relation to slat-blinds or 25 so-called "Venetian" blinds for windows; and it consists in the improved construction and combination of parts of a blind, in which the slats are formed upon their inner edges with cylindrical beads, which are engaged by circular notches in the edge of an adjusting-rod, 30 all staples or hinges being dispensed with, as hereinafter more fully described and claimed.

In the accompanying drawings, the letter A indicates the frame of the blind, which frame 35 may be of any desired construction, and the letters B indicate the slats, the trunnions C of which are pivoted in bores in the inner edges of the side pieces of the frame. The inner edges of these slats are formed with cylindrical beads E, and these beads form grooves F in the outer sides of the slats, and a rod, G, is formed with a number of circular notches or recesses, H, in its edge fitting upon these beads, the notches comprising slightly more 40 than one-half of a circle. The notches by means of which the adjusting-rod may be slid upon the beaded edges of the slats from the ends of the slats are formed so that their upper sides will form pointed shoulders I, which 45 may bear into the grooves in the outer sides of the slats, stopping the slats from being tilted farther than into a horizontal position.

The upper and lower slat in a series of slats are formed with a notch or kerf, J, in the middle of the bead, and pins K are driven through 55 the rod projecting into the notches in the ends of the rod and project into these notches or kerfs, retaining the rod upon the slats and preventing it from sliding laterally. The lower end of the adjusting-rod is provided with a 60 plate, L, pivoted to the same, and this plate is provided with a longitudinal slot, M, having notches N in one edge, the slot fitting over a pin or bolt, O, projecting from the frame of the blind and engaging the notch, which may 65 be placed upon the bolt. The outer or lower edges of the slats will rest in the grooves of the slats below when the slats are tilted vertically, forming a perfect closure, excluding light and rain or other dampness.

The entire blind may be made without the use of metal in any of the parts, and the slats and the adjusting-rods may easily be made with simple machinery or tools. The joints between the slats and the adjusting-rod will be 70 75 strong, and will at all times be movable, as they are not liable to be clogged up with rust or dirt, as the metallic joints, and the notches being made in the edge of the rod, in which the grain of the wood runs lengthwise, the entire piece between two notches will have to be broken out before the slat may be disengaged from the notch.

In painting the blinds the pins may be removed from the adjusting-rods and the adjusting-rods slid to one side, slipping off the beads at the ends of the slats, and the slats may now be tilted and revolved so as to bring both sides and the edges in convenient position for painting them, and when the paint is dry the rod 80 85 may be slid in place again and the pins inserted, when the blinds will again be in order.

Having thus described my invention, I claim and desire to secure by Letters Patent of the United States—

1. In a window-blind, the combination of slats having cylindrical beads upon their upper edges, with an adjusting-rod having circular notches in its edge fitting upon the beaded edges of the slats, as and for the purpose 90 100 shown and set forth.

2. In a window-blind, the combination of slats having cylindrical beads upon their upper edges forming grooves upon their outer

sides near the said edges, with an adjusting-rod having notches in its edge comprising slightly more than a semi-circle and formed with pointed shoulders at the upper sides engaging the grooves in the slats, as and for the purpose shown and set forth.

3. In a window-blind, the combination of a series of slats having cylindrical beads upon their upper edges forming grooves upon the outer sides near the said edges, and having notches or kerfs in the middles of the beads of the upper and lower slat, an adjusting-rod having notches comprising slightly more than a semi-circle in its edge and formed with pointed shoulders at the upper sides of the notches engaging the grooves in the slats, and pins inserted through the ends of the adjusting-rod, entering the notches in the ends and

the kerfs in the end slats, as and for the purpose shown and set forth. 20

4. In a window-blind, the combination of a series of slats having their upper edges formed into cylindrical beads, an adjusting-rod having circular notches in its edge engaging the beads, a longitudinally-slotted plate at the end of the rod having notches in one edge and the engaging-pin in the blind-frame, as and for the purpose shown and set forth. 25

In testimony that I claim the foregoing as my own I have hereunto affixed my signature in presence of two witnesses. 33

JOHN JOHNSON GULDHANG.
